UNITED STATES PATENT OFFICE.

JAMES A. WOTTON, OF ATLANTA, GEORGIA, ASSIGNOR OF ONE-HALF TO
JOHN D. EASTERLIN, OF SAME PLACE.

SAFETY-FUSE FOR ELECTRIC CONDUCTORS.

SPECIFICATION forming part of Letters Patent No. 466,761, dated January 5, 1892.

Application filed October 12, 1891. Serial No. 408,508. (No model.)

To all whom it may concern:

Be it known that I, JAMES ASHLEY WOTTON, of Atlanta, in the county of Fulton and State of Georgia, have invented certain new and useful Improvements in Safety-Fuses for Electric Conductors; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates, as above stated, to safety-fuses for preventing the passage of a high-tension current to any delicate instrument over a small wire normally carrying a current of a low tension and also to set a limit to the increment of the normal current.

To this end the invention consists in providing a substance having a high electrical resistance and a comparatively low specific heat, such as a graphite or a mixture of graphite and clay or any of the forms of carbon having a high electrical resistance, with metallic terminals for including it in the circuit of the apparatus to be protected and of arranging a suitable explosive within such carbon or terminals or between them as will 30 explode and disrupt the circuit upon the heating of said carbon by the passage of the vagrant current, said explosion also serving to blow out or break any arc which might form between the two terminals in exceptional cases.

The invention will be hereinafter fully described, and is shown in the accompanying drawings, in which—

Figure 1 is a view of the device, partly in section, showing the carbon with the terminals on its end and by the section showing the contents of one of the terminals. Fig. 2 is a like view showing the explosive within the carbon. Fig. 3 is a cross-section of Fig. 2, further illustrating the elements therein shown.

In the figures like reference-marks indicate corresponding parts in all the views.

1 indicates the wires, and 2 the terminals thereon, 3 being a small stick or piece of car-

bon or other material possessing high resistance to the passage of the electrical current and a low specific heat. The terminals 2 are preferably of copper and fit over the ends of the carbon 3, while an explosive—such as 55 gun-cotton, mercury fulminate, or other suitable explosive—is placed within that part of the cap 2 which is not occupied by the carbon. One or both of the terminal-caps 2 may be thus charged.

In Figs. 2 and 3 a modification of the device is shown wherein the explosive is placed within the carbon and whereby a heavier explosive discharge may be obtained, which would obviously break a heavier arc or high-resistance element than would a smaller discharge, and the action of the device would be more certain in its disruptive action. If desired, a fusible wire 4, Fig. 2, having a melting-point slightly higher than the temperature at which the explosion takes place may be incorporated in the inleading wire and should be connected intimately with the cap or terminal to obtain the best results. The heat generated in the carbon or other 75 high-resistance material will be communicated to the caps and melt the fuse-wire in case the explosive does not ignite at its calculated limit.

Having thus described my invention, what 80 I claim as new, and desire to secure by Letters Patent, is—

1. In a device of the class specified, a fragile high-resistance element in circuit and an explosive substance associated therewith in 85 such a manner as to be ignited upon the heating of said high-resistance element, for the purpose specified.

2. In a device of the class specified, a fragile high-resistance element in circuit, a metallic cap thereon, and an explosive substance within said cap in the portion not filled by said element, for the purpose specified.

3. In a device of the class specified, the high-resistance element secured at one end 95 to one circuit-wire, a cap containing an explosive substance secured to the other wire and having the end of said high-resistance element inserted therein, for the purpose specified.

4. In a device of the class specified, a metallic terminal and a high-resistance terminal in contact over part of their surfaces and an explosive substance so arranged between
5 said terminals as to explode and break the circuit upon the heating of the high-resistance terminal, for the purpose specified.

In testimony whereof I hereunto affix my signature in presence of two witnesses.

JAMES A. WOTTON.
